UNITED STATES PATENT OFFICE.

GEORGE A. FREDENBURGH, OF PAWTUCKET, RHODE ISLAND.

THREAD-DRESSING MACHINE.

SPECIFICATION forming part of Letters Patent No. 782,192, dated February 7, 1905.

Application filed January 21, 1904. Serial No. 190,053.

To all whom it may concern:

Be it known that I, GEORGE A. FREDENBURGH, a citizen of the United States, residing in the city of Pawtucket, in the county of 5 Providence and State of Rhode Island, have invented certain new and useful Improvements in Thread-Dressing Machines, of which the following is a specification.

My invention relates to thread-dressing 10 machines, and more especially to the brushes and thread-ironers thereof; and it consists of the novel construction of the several parts, as hereinafter described, and specifically set forth in the claims.

15 My present invention relates to improvements on certain parts of the thread-dressing machine described and claimed in Letters Patent of the United States, No. 702,786, issued to me June 17, 1902.

20 Figure 1 is a front elevation of my improved thread-dressing machine. Fig. 2 is a central longitudinal sectional view taken on line *x-x* of Fig. 1. Fig. 3 is a similar sectional view taken on line *y-y* of Fig. 1. Fig. 4 is an enlarged cross-sectional view of the machine, taken on line *z-z* of Fig. 1. Fig. 5 is a perspective view of a modified form of a thread-ironer. Fig. 6 is a central longitudinal sectional view of the driving end portion of the 25 brush.

Like numerals indicate like parts.

In the drawings, 11 represent the standards forming a part of the framework of the machine. Steam enters through the pipe 2, which at intervals is provided with elbows and T-couplings, of which five are shown at the right of Fig. 1, (designated as 3, 4, 5, 6, and 7, respectively.) The pipe 2 is made up of sections united by the T-couplings 3, 4, 5, and 6. 35 The steam passes from the machine through the pipe 8, made up of sections, which are united by the T-couplings 9, 10, 11, and 12. A pipe 13 extends horizontally from the elbow 7 to the elbow 14. A pipe 15 extends from the 40 T-coupling 6 to the T-coupling 12. A pipe 16 extends from the T-coupling 5 to the T-coupling 11. A pipe 17 extends from the T-coupling 4 to the T-coupling 10. A pipe 18 extends from the T-coupling 3 to the T-coupling 9. A stationary ironer 19 is a tube hav-

ing integral collars 20 20 and reduced tubular ends 21^a. These collars 20 abut the inner sides of the standards 11 of the frame of the machine, and so prevent endwise movements of said tube 19, and the reduced tubular ends 21^a pass through bearings made therefor in the standards 11. In like manner the stationary ironer 21 is a tube having integral collars 22 22 and reduced ends 23 23. The collars 22 22 are in abutment with the standards 11 of the frame and prevent endwise movements of the tube 21, and the reduced ends 23 23 of the tube 21 pass through bearings made therefor in said standards 11.

The stationary ironer 21 surrounds concentrically the steam-pipe 15, which pipe is of such diameter as to fit snugly in the reduced ends 23 23 of the tubular ironer 21, and there is left an annular space between the exterior surface of the pipe 15 and the interior surface 65 of the tubular ironer 21, as fully illustrated in Fig. 2. The ironer 21 is heated by radiations from the steam-pipe 15 in said annular space. In like manner the steam-pipe 13 passes through the stationary ironer 19. On both 70 the stationary ironers 19 and 21 are a series 75 of circumferential grooves 24.

The stationary ironer 21 is fastened in position by the plates 25 25, bolted at 26 26 to the standards 11. Set-screws 27 27, through 80 the plates 25 25, have their inner ends bear against the reduced ends 23 23 of the ironer 21, and thus the ironer 21 is held from rotation upon the machine-frame. In like manner the ironer 19 is held fixed in position by plates, 85 bolts, and set-screws, as illustrated in Fig. 1.

The ironer 28 is a tube. (Shown in elevation in Fig. 1 and in central horizontal section in Fig. 3.) It has a series of circumferential grooves 29. Collars 30 30', integral 90 with the ironer 28, are provided, beyond which the tube 28 is reduced in diameter to form annular flanges 31 31, which are beveled to receive balls 32 32. The bore of these reduced ends is of such diameter as to loosely receive 95 the steam-pipe 16, which passes through the tubular ironer 28 concentrically. Sleeves 33 33 are slidably mounted on the pipe 16 and have annular beveled edges to receive said balls. These sleeves 33 33 are held in proper 100

position with relation to the annular flanges 31 31 of the ironer 28 to form circular V-shaped grooves for said balls by means of collars 34 34, which are fastened in place on 5 the pipe 16 by set-screws 35 35. On one end of the ironer 28 is a gear 36, which abuts the collar 30 and is keyed or otherwise fastened to the ironer 28, so as to rotate the same.

The ends of the steam-pipe 16 pass through 10 bearings 37 37 in the standards 1 1 and are held fast in position by the plates 38 38, bolted at 39 39 to the standards 1 1, and by the set-screws 40 40, which pass through the plates 38 38 and bear against said pipe 16.

15 On one of the standards 1 is a tubular bearing 41, in which is fastened a short shaft 42 by means of a set-screw 43. On said shaft 42 is loosely mounted a driving-gear 44, which meshes with the gear 36 of the rotating 20 ironer 28. A collar 45 on the shaft 42 is fastened by a set-screw 46 and holds the gear 44 from outward displacement. The gear 44 has a long hub, whose inner end abuts the surface of a boss 47 on the standard 1, as shown in 25 Fig. 3. A pulley 48 is keyed or otherwise fastened to the hub of the gear 44. A belt 49 passes over the pulley 48 to turn the same, and thus the driving-gear 44 is rotated. This pulley 48 is driven by the belt 49, which also 30 passes over the pulley 50 on the driving-shaft 51, Fig. 4.

The pipe 17, extending from the T-coupling 4 to the T-coupling 10, is fastened by bearings, plates, and set-screws in the same manner that the pipe 16 is and is surrounded by a rotary ironer 52, in all respects like the rotary ironer 28 and similarly mounted and furnished with ball-bearings, &c. The rotary ironer 52 has a gear 53 and circumferential 40 grooves 54. The gear 53 meshes with the driving-gear 55, which is mounted on the shaft 56, that is fixed to the machine-frame in a manner similar to shaft 42. On the hub of the gear 55 is made fast a pulley 57. A 45 belt 58 from the driving-pulley 50 of the shaft 51 turns the pulley 57 of the gear 55.

The pipe 18, extending from the T-coupling 3 to the T-coupling 9, is fastened by bearings, plates, and set-screws in the same manner as the pipe 16 and is surrounded by the rotary tubular brush 59, which is provided with the bristles 60. The construction of this brush 59 is substantially the same as that shown in United States Letters Patent No. 55 746,946, issued to me December 15, 1903. This brush 59 is made fast upon a tubular shaft 18^a, which loosely surrounds the steam-pipe 18, as seen in Fig. 4, and said shaft has its ends made solid, so as to form hubs, as shown, at 60 18^b in Fig. 6, and these hubs loosely surround said pipe 18 and have their interior surfaces beveled inwardly, as seen in said figure. A sleeve 33^a on the pipe 18 is made to enter each end of the tubular shaft 18^a and is beveled inwardly, so that between the hubs 18^b

of said tubular shaft and sleeves 33^a are formed V-shaped channels, in which balls 32^a are mounted. The brush 59 is prevented from endwise movement on the steam-pipe 18 by collars which abut the sleeves 33^a, as shown 70 at 34^a in Fig. 6, and these collars are fastened in place upon the pipe 18 by set-screws in the same manner as for the rotary ironers 28 and 52. A gear 61 is made fast upon one hub of the tubular shaft 18^a and meshes with the driving-gear 62 on shaft 63. Said driving-gear 62 is loosely mounted on a short shaft 63, and on the hub of the gear 62 is keyed a pulley 64. The shaft 63 is fixedly secured to a standard 1 and has a collar fastened by a set-screw to 80 hold the gear 62 from outward displacement in the same manner as for the driving-gears 44 55 of the rotary ironers. A belt 65 from the driving-pulley 50 on the shaft 51 rotates the pulley 64, mounted on the hub of the gear 62. By the crossing of the belt 58, as shown in Fig. 4, the gear 55 is driven in a direction opposite to that of the rotation of the gears 44 and 62.

On portions 66 of the frame of the machine 90 rods or bars 67 are adjustably mounted and held in position by the set-screws 68. Peripherally-grooved rollers 69 are mounted on the outer ends of said rods or bars 67, respectively. Said rods or bars 67, with their rollers 95 69, constitute the means for regulating the desired tension of the thread upon the brush and ironers.

A bracket 70 is mounted on a portion 71 of the machine-frame by bolts 72. A pulley 73 100 rotates a shaft which is mounted in said bracket and is driven by a belt 74. A gear 75 rotates with said shaft and meshes with a gear 76, which carries a twisting-head 77. Each twisting-head 77 has thread-guides 78 105 and 79.

Having thus described the parts of my improved thread-dressing machine, I will proceed to explain its operation. The thread 80 having passed from the reel and having been carried through the trough of sizing liquid (not shown, because they do not constitute any part of my present invention, but are shown in my said prior patent of June 17, 1902) goes up through the thread-guide 79, the twisting-head 77, and the thread-guide 78 and is twisted by the gearing and pulley 76 75 73, driven by the belt 74. The thread 80 so saturated and twisted first comes into contact with the bristles 60 of the cylindrical brush 59, and the projecting fibers of the thread are properly laid by the brush operation. The steam enters the pipe 2, passes thence through the pipes 18, 17, 16, 15, and 13, and thence passes out through the pipe 8. Between said pipes 13, 15, 16, 17, and 18 120 and the tubes 19, 21, 28, 52, and 59, which surround said pipes, respectively, are annular spaces, as shown in Figs. 2, 3, and 4, so that the radiation of heat from said pipes through 125 said annular spaces heats said tubes. The 130

steam heat in the cylindrical brush and brush-shafting causes the rapid drying of the saturated thread. The thread 80 next passes up and behind the lower tension-roller 69 in the 5 groove thereof and thence behind the rotary ironer 52 in the groove 54 thereof, thence in front of the rotary ironer 28 in the groove 29 thereof, thence behind the stationary ironer 21 in the groove 24 thereof, thence in front 10 of the stationary ironer 19 in the groove 24 thereof, thence behind the upper tension-roller 69 in the groove thereof, and thence is carried to the spools (not shown) and wound thereon, as usual, the draft on the thread being caused by the winding mechanism. By this travel of the thread 80 over the ironers in the grooves thereof the thread is ironed and polished, the rate of rotation of the rotary ironers 28 and 52 being more rapid than 15 the rate of travel of the thread which passes over them. These peripheral grooves in the ironers are half-round, and therefore as the thread passes alternately behind and in front of these ironers one after the other in the series 20 the thread is ironed all around and equally. The tension devices cause the thread 80 to be drawn tightly in this ironing operation. The lower ironers 52 and 28, which first operate on the thread 80 to smooth and polish 25 it, are rotary and turn in the directions indicated by the arrows *a* and *b*; but the ironers 21 and 19 do not rotate, but are stationary, and therefore are adapted to impart the final 30 finish to the thread. The stationary ironers 19 21 from time to time may be moved in order to present a different peripheral surface 35 to the thread as the latter passes over them. This is done by loosening the set-screws, slightly turning the ironers 19 21, and then 40 tightening the set-screws again. In this manner the uneven wear of the surface of said ironers is prevented.

In Fig. 5 I show a modification of the ironers in which the circumferential grooves are 45 omitted and the surface is perfectly smooth and cylindrical.

I claim as a novel and useful invention and desire to secure by Letters Patent—

1. In a thread-dressing machine, the combination with the frame of said machine, of two 50 bearings each having a flat front surface, a tubular ironer having two collars which are in abutment with said frame and also having reduced ends beyond said collars, which reduced 55 ends have their bores of less diameter than the bore of said tubular ironer, two bearing-plates bolted to the flat front surfaces of said bearings, a steam-pipe of uniform diameter passing through said tubular ironer and 60 through said reduced ends thereof, and set-screws passing through said plates and having their inner ends in contact with said reduced ends respectively of said ironer, substantially as specified.

2. In a thread-dressing machine, the combi-

nation of a steam-pipe, a rotatable tubular ironer having its bore reduced at its two ends and also having said ends provided with an interior annular beveled surface, two beveled-edged sleeves mounted on said pipe and forming 70 with the ends of said ironer two V-shaped circumferential grooves, balls mounted in said grooves, two collars mounted on said pipe, and set-screws passing through said collars into contact with the steam-pipe for the purpose of holding said beveled-edged sleeves in 75 said position, substantially as specified.

3. In a thread-dressing machine, the combination of a driving-pulley, a gear having a pulley driven by a belt from the first-named pulley, a second gear having a pulley driven by a belt from the first-named pulley, a steam-pipe, a rotatable tubular ironer mounted on 80 said steam-pipe and provided with a gear which meshes with the first-named gear, a second steam-pipe, and a second rotatable tubular ironer mounted on the second-named steam-pipe and provided with a gear which meshes with the second-named gear, substantially as 85 described.

4. In a thread-dressing machine, the combination of a driving-pulley, a gear having a pulley driven by a belt from the first-named pulley, a second gear having a pulley driven by a crossed belt from the first-named pulley, 90 a steam-pipe, a rotatable tubular ironer mounted on said steam-pipe and provided with a gear which meshes with the first-named gear, a second steam-pipe, and a second rotatable tubular ironer mounted on said second-named 95 steam-pipe and provided with a gear which meshes with the second-named gear, substantially as 100 specified.

5. In a thread-dressing machine, the combination of a driving-pulley, a gear having a pulley driven by a belt from the first-named pulley, a second gear having a pulley driven by a crossed belt from the first-named pulley, tension devices adapted to give proper tension 105 to the thread which is to be dressed by said machine, a steam-pipe, a rotatable tubular ironer mounted on said steam-pipe and provided with a gear which meshes with the first-named gear, a second steam-pipe, and a second rotatable tubular ironer mounted on said second-named 110 pipe and provided with a gear which meshes with the second-named gear, substantially as 115 specified.

6. In a thread-dressing machine, the combination of a main shaft, a gear driven in one direction by suitable means from the main shaft, a second gear driven in the opposite direction by suitable means from the main shaft, a rotatable tubular ironer having a gear which meshes with the first-named gear, a steam-pipe 120 on which said ironer is mounted, a second rotatable tubular ironer having a gear which meshes with the second-named gear, a second steam-pipe on which said second-named ironer 125 is mounted, a third steam-pipe, a stationary 130

tubular ironer mounted on said third-named steam-pipe, and means for regulating the desired tension of the thread upon said ironers, substantially as specified.

- 5 7. In a thread-dressing machine, the combination of a main shaft, a gear driven in one direction by suitable means from the main shaft, a second gear driven in the opposite direction by suitable means from the main shaft, a 10 rotatable tubular ironer having a gear which meshes with the first-named gear, a steam-pipe on which said ironer is mounted, a second rotatable tubular ironer having a gear which meshes with the second-named gear, a second 15 steam-pipe on which said second ironer is mounted, a third steam-pipe, a stationary tubular ironer mounted on said third-named steam-pipe, a fourth steam-pipe, a second stationary tubular ironer mounted on said fourth- 20 named steam-pipe, and means for regulating the desired tension of the thread upon said four ironers, substantially as specified.

8. The improved thread-dressing machine herein described consisting, of five parallel 25 steam-pipes arranged in substantially the same plane, an inlet steam-pipe into which one end of each of said five steam-pipes enters, an outlet steam-pipe into which the opposite end of each of said five steam-pipes enters, a driv- 30 ing-pulley, a gear rotatably mounted on the machine-frame, a pulley keyed upon the hub of said gear and driven by a belt from the first-named pulley, a second gear rotatably mounted

on the machine-frame, a second pulley keyed upon the hub of said second-mentioned gear 35 and driven by a belt from the first-named pulley, a third gear rotatably mounted on the machine-frame, a third pulley keyed upon the hub of said third-mentioned gear and driven by a belt from the first-named pulley, a rota- 40 table cylindrical brush mounted on the first of said five steam-pipes, a gear made fast upon said brush and in mesh with the first said gear, a rotatable tubular ironer mounted on the sec- 45 ond of said five steam-pipes, a gear made fast upon said ironer and in mesh with said second-mentioned gear, a rotatable tubular ironer mounted on the third of said five steam-pipes, a gear made fast upon said second-mentioned ironer and in mesh with said third-mentioned 50 gear, a stationary tubular ironer mounted on the fourth of said five steam-pipes, a stationary tubular ironer mounted on the fifth of said five steam-pipes, all of said ironers provided each with a series of circumferential grooves 55 forming thread-passages arranged in vertical alinement with each other, and tension devices adapted to give proper tension to the thread which is dressed by said machine, substan- 60 tially as specified.

In testimony whereof I affix my signature in presence of two witnesses.

GEORGE A. FREDENBURGH.
